(57) **CLAIM**

The ornamental design for an electrical outlet box for recessed plug in, as shown and described.

DESCRIPTION

FIG. 1 is a front perspective view of the electrical box of the present invention showing a hole in the rear wall.

FIG. 2 is a rear perspective view of the electrical box of the present invention.

FIG. 3 is a front elevation view of the box.

FIG. 4 is a rear elevation view of the box.

FIG. 5 is a side elevation view of the box, with the opposite side view being identical; and,

FIG. 6 is a top plan view of the box, with the bottom plan view being identical.
